UNITED STATES PATENT OFFICE

2,619,771

TOY FIGURE

Olive M. Jones, East Haddam, Conn.

Application July 24, 1947, Serial No. 763,301

2 Claims. (Cl. 46—154)

1

This invention relates to dolls, toys in form of animals or figures and similar devices for entertainment, playing or like purposes.

It has heretofore been proposed to construct toys consisting of a hollow body in which the fingers of a person's hand were inserted to bring about simulation of movements of such body. Some of these known toy devices are shaped in such manner that the fingers of the hand form complementary parts of the figure or doll body which may be actuated by moving these fingers.

Other known structures of the aforesaid type employ as a toy body a mitten in which the fingers of a person's hand are inserted to move head and/or paws of an animal which are attached to the ends or finger tips of such mitten.

The present invention has reference to a doll or like toy figure whose body, which may be stuffed or otherwise stiffened, preferably constitutes a complete unit in itself and has as one of its main objects means for manipulating or operating predetermined body parts relatively to the remainder of the body to enhance animation and maneuverability of the toy figure.

It is another object of the present invention to provide means offering the possibility of novel effects produced by the handling of and playing with articles or elements carried by the toy figure.

Still another object of the invention is to provide means for maintaining the toy figure in upright position independently of the insertion of the fingers of the hand of an operator.

Yet another object of the invention is to provide means affording rigid extensions of the finger tips of the hand with which extensions movements of articles or elements are brought about, which may be carried or held in pockets or other openings of the covering of the toy figure.

Still a further object of the invention resides in the provision of means for actuating the toy figure in a manner similar to that of a magician and for obtaining unexpected displacements of elements or articles with respect to each other, when contained in the covering or suit of said toy figure.

Another object of the invention is to provide means facilitating the insertion of the hand of a person behind the covering of the toy figure for obtaining access to particular body parts to be manipulated and swung.

Other objects of the invention will be pointed out in the following description and claims and illustrated in the accompanying drawings which

2

disclose, by way of example, the principle of the invention and preferred modes which have been contemplated for applying said principle.

In the drawings:

5 Fig. 1 is a front elevation view of a toy figure embodying the invention, a part of the sleeve of the figure being broken away to show inner portions of said toy figure.

10 Fig. 2 shows the upper part of the toy figure of Fig. 1 in a different position.

Figs. 3 and 4 illustrate parts of the toy figure as seen in two different positions, respectively.

Fig. 5 is a fragmentary vertical, sectional view of the toy figure seen in Fig. 1.

15 Referring now more particularly to the drawings, there is shown in Fig. 1 a toy figure 10 having a stuffed body with covering including a head 11, a blouse 12 and a pair of trousers 13. Blouse 12 is provided with two hollow sleeves 14 and 15 20 to which are attached respective hands 16, 17 made of relatively stiff or rigid material, such as plastic or plastic composition.

25 Each of the hand members 16, 17 has an inner extension 18 which, as exemplified in Fig. 1, projects into the sleeves, such as shown with respect to sleeve 15 which is partly broken away in order to indicate the position of hollow extension 18 which is used for the insertion of one of the fingers of a person's hand.

30 The pair of trousers 13 is provided with side pockets 19, 20 which communicate with each other. The upper part of trousers 21 is provided with an inner elastic band 22 to keep the upper trouser part in position above the blouse 35 12 which in this instance is tucked in underneath the trousers.

35 The elastic band 22 permits communication from pockets 19, 20 to the upper trouser portion 21. The trouser pockets are formed rearwardly 40 of outer trouser wall 23 by a lining 23a, as will be later explained and which may carry several articles, such as a miniature turtle 24, an egg 25 and a fish figure 26, all of which being held in position behind wall 23 and thus hidden from view.

45 Fig. 2 illustrates how the turtle 24 placed in the pocket of toy figure 10 may be removed therefrom by manipulating hand members 16 and 17. To this end hand members 16, 17 are inserted into side pockets 19 and 20 and moved so as to lift the turtle figure 24 beyond the upper trouser part 21 and elastic band 22 which is held in position by stitches 22a, 22b connecting the corners of wall 23 to trouser parts 13a, 13b.

55 In order to arrive at such operation, reference

is herewith made to Fig. 5 which shows the body of the toy figure 10 stuffed with a suitable filling material 27 customary in the toy industry. The rear part 12a of the blouse 12 of the toy figure is used for accommodating and covering the hand of the operator. The blouse 12 is normally held in taut condition on the body of the toy figure 10 by means of an elastic band 12b, but is allowed to be moved according to arrow A into a position indicated in dot dash lines upon insertion of the hand of the operator.

A suitable recess or finger rest 28 is provided in the head of the toy figure for placing therein the index finger 29, whereas the middle finger 30 and the thumb 31 of the hand are inserted respectively in the hollow sleeves 14 and 15 of the blouse 12. At the end of each sleeve, and as hereinabove explained, there is affixed at 32 hollow extension 18 which may be made from cardboard, plastic or suitable stiff material. Each extension has a flange 33 with perforations 34 in order to fix said extensions 18 in position at the extremities of sleeves 14 and 15.

As can be seen in Fig. 1, the middle finger 30 and thumb 31 frictionally engage within the blouse 12 the outwardly flared ends of extension 18 to thereby facilitate operation and movements of hands 16 and 17 of the doll or toy figure.

As can be further seen from Fig. 5 the reinforced rear wall 35 of the stuffed body proper of the toy figure is connected with the front wall 40 thereof at a location below head 11 and below the end of finger rest or recess 28 thereof. The body rear wall 35 includes a forwardly slanting wall 39, which may constitute the continuation of the inner lining or covering 36 of rear wall 35. Wall 39 thus forms a guide for the insertion of the fingers of the hand of the operator in pocket 41 and also serves as a rest for the palm of the hand, when the latter is slipped under the yieldable blouse rear part 12a which closes pocket 41. The body wall 39 is stitched or otherwise connected at 37 to the lower end of hollow head 11. Blouse rear part 12a is likewise affixed to the lower head end at 37a, whereby finger rest or recess 28 in body portion 11 forms a complementary part of pocket 41.

In order to conceal the fixation at 37 a simulated scarf or collar 38 is employed, which is either permanently or detachably secured to the toy or like body, the latter being made from any appropriate material, such as cardboard, fabric, pliable plastic composition, etc.

As will be realized from the drawings, blouse 12 and the upper part 21 of the front wall of the trousers 13 are so constructed that the lower front part 12c of blouse 12 may be either tucked in underneath the upper part 21 of the trousers (Figs. 1 and 2) or may be concealed and held (by means of rubber band 12b) on top of the upper part 21 of the trousers 13 (Figs. 3 to 5). Such construction of the outer covering parts of the toy figure enables the operator to bring about various manipulations and movements of toy figure elements similar to those performed by a magician.

For instance, as seen in Fig. 3 article 25 placed in the front trousers pocket is readily lifted and pushed by manipulation of hand 17 (inserted in pocket at 20) beyond the upper part 21 of trousers 13, while the lower blouse part 12c is held in taut condition by means of the elastic band 12b on top of the trousers 13. Egg article 25 is held in this position (Fig. 3) by hand 17

and if subsequently the lower blouse part 12c (Fig. 4) is lifted by hand 16 and removed from above the upper part 21 of said trousers, the egg article 25 becomes visible and can entirely be pushed out of the pocket which, in this instance, is formed by lining 23a extending between the outer wall 23 of trousers and front wall 40 of the toy figure as clearly seen in Fig. 5. Lifting of the front part 12c of the blouse 12 and removal of article 25 may be had by manipulation of finger 30 and thumb 31, which are inserted in extensions 18 of the hands 16 and 17.

As further seen in Fig. 1, if the pocket contains several articles hand 16, when placed in one end 18 of the pocket of the trousers 13 may push one of the articles, designated by numeral 26, sidewardly out of the other end 20 of the pocket whereby also unexpected effects will be attained.

It is quite obvious that instead of a toy figure, animal or other imitation bodies may be employed for the purpose of the invention incorporating the features thereof.

The body of the toy is preferably so shaped and constructed, that the covering therefor includes at the front and back thereof the oppositely directed pockets 41, 42 of which the rear pocket 41 lends itself to the accommodation of the hand and fingers of the operator, whereas the front pocket 42 is employed to hold any suitable objects or articles for removal from and/or displacement in said front pocket by simply manipulating the finger holders 16, 17 from said rear pocket. If desired, said front pocket may be temporarily hidden from view by a portion of the covering such as lower blouse part 12c, which may extend to lie over said front pocket.

It can thus be seen that there has been provided in accordance with this invention a figure in the form of a toy having a body of relatively stiff material and a flexible covering therefor, which includes a glove-shaped portion arranged on the back of said body, two finger holders, respectively, connected to said glove-shaped portion and movable relatively to the remainder of said covering, a pocket disposed at the front of said body, said pocket terminating in an upper edge, said upper edge being provided with an elastic element to maintain said upper edge in taut condition, fingers of an operator's hand being engageable with said finger holders, respectively, to displace an article when contained in said pocket. The front pocket is preferably also provided with side openings, which communicate with the opening at the upper edge of said pocket.

As many possible embodiments may be conceived of the above invention, and as alterations and changes may be made in the embodiments above set forth, it is to be stated that all matters hereinbefore explained or shown in the accompanying drawings, are to be interpreted as illustrative and not in a limitative sense.

Having thus described the invention, what is claimed as new and desired to be secured by Letters Patent is:

1. In a toy figure having a stuffed body throughout its length and including an upper body portion with head; a covering extending over said body and including a blouse and two arm sleeves, a first pocket extending on one side of said covering in downward direction of said body, a second pocket extending on the opposite side of said covering in upward direction and partly into said head to thereby provide a finger rest therein, each

of said arm sleeves being provided with a substantially rigid hollow hand member, said first pocket being provided with sidewardly directed end openings and with an upwardly directed opening perpendicularly to said end openings, whereby articles in said first pocket may be displaced therein for removal therefrom through one of said openings, said second pocket being adapted to receive the hand of an operator with one of his fingers in engagement with said finger rest and with other fingers inserted through said sleeves in said hand members, said sleeves and said hand members being of sufficient lengths to reach into said first pocket for operating said articles therein and to displace same, said blouse being provided at its lower edge with an elastic band, said lower edge being adapted to extend over at least one of said openings of said first pocket to conceal same.

2. In a toy figure according to claim 1, wherein the upwardly directed opening of said first pocket is defined by an elastic strip to normally hold

said first pocket in substantially taut and closed condition.

OLIVE M. JONES.
